UNITED STATES PATENT OFFICE

2,413,387

TRACK SANDER

Leon E. Simmons, Claremont, N. H., assignor to
 Joy Manufacturing Company, a corporation of
 Pennsylvania

Application April 19, 1944, Serial No. 531,777

6 Claims. (Cl. 291—28)

1

This invention relates to track sanders and more particularly to improvements in track sanders embodying sand feeders of the oscillatory type.

In vehicles of the wheel-mounted type, particularly railway vehicles wherein slippage may oftentimes occur between the track wheels and the rails of the trackway, for instance when the trackway is inclined with respect to the horizontal and the wheels tend to loose their traction, it is necessary to apply sand to the rail treads to increase the friction. In vehicles such as the wheeled trucks of coal mining apparatus, various known devices have been provided for feeding sand to the track rails, but such devices have not been satisfactory, especially when the sand is wet or packed and are frequently completely abandoned as useless.

An object of the present invention is to provide an improved track sander whereby the disadvantages of previous known devices are substantially overcome. Another object is to provide an improved track sander having improved feeding means. A further object is to provide an improved sand feeder of the oscillatory type. Yet another object is to provide an improved, oscillatory type sand feeder having a sliding shoe yieldingly held in contact with the bottom wall of the sand container for controlling the flow of sand through a bottom discharge opening. Other objects and advantages of the invention will, however, hereinafter more fully appear.

In the accompanying drawing there is shown for purposes of illustration one form which the invention may assume in practice.

In this drawing:

Fig. 1 is a fragmentary plan view of a railway vehicle equipped with a track sander constructed in accordance with an illustrative form of the invention.

Fig. 2 is a fragmentary side elevational view of the vehicle and track sander shown in Fig. 1.

Fig. 3 is an enlarged cross sectional view taken substantially on line 3—3 of Fig. 1.

Fig. 4 is an enlarged view in longitudinal vertical section with parts shown in side elevation taken substantially on line 4—4 of Fig. 1.

In this illustrative construction, there is shown a railway vehicle, generally designated 1, equipped with the improved track sander, generally designated 2. The railway vehicle shown is herein a transport truck for a coal mining machine, although it will be evident that the improved track sander may be associated with vehicles of various other types.

2

The vehicle 1 comprises a truck frame 3 mounted on wheels 4 adapted to travel along the rails 5 of a trackway. Carried by the truck frame and overlying the track sander 2 is a frame 6 for receiving and supporting a conventional type of coal mining machine. At one side of the truck frame is a platform 7 providing a station for the operator during traveling of the vehicle along the trackway. The improved track sander 2, in this 10 illustrative construction, comprises a pair of hopperlike containers or sand receptacles 8, 8 preferably of substantially rectangular shape in horizontal section and having a curved bottom wall 9. These sand containers are arranged at opposite sides of the truck frame longitudinally between the truck wheels and are secured as by brackets 10 bolted at 11 to parts of the truck frame. The containers each have a detachable top cover 12 provided with a handle and which is removable 20 to permit filling of the containers with sand. Extending across the truck frame beneath the frame 6 is a horizontal shaft 13 extending into and across the containers and suitably journaled in the container side walls. Attached to one end 25 of this shaft is a lever 14 to which an operating rod 15 is pivotally connected at one end at 16. The other end of this rod is provided with a handle 17 which may be grasped by the operator. This handle is located near the operator's station 30 on the platform 7, and when not in use a portion of the rod 15 near the handle is receivable in a slot or notch 18 in a vertical plate 19 suitably secured to the truck frame. Arranged in each of the containers is an oscillatory feeder and agitating arm member 20. These members 20 have their hubs secured to the cross shaft 13; and spacer sleeves 21 surrounding the shaft 13 suitably locate the arm hubs on the shaft and locate the shaft transversely of the truck. The arms 40 each have a tubular portion 22 in which a cylindrical stem 23 of a shoe 24 is slidably received. Coiled springs 25 in the tubular portions 22 of the arms urge the shoes 24 into firm frictional contact with the bottom wall of the container, 45 and the shoes are curved at 26 to conform to the curved surface of the bottom container wall. Each of the containers has a bottom discharge opening 27 and flow of sand through these openings is controlled by the shoes 24 as the latter 50 move over the openings. Flexible conduits such as sections of flexible hose 28 direct the discharging sand toward the treads of the track rails. The lower ends of the hoses 28 may be shaped to appropriately distribute the sand over the 55 rail treads. Each of the shoe stems 23 has se-

cured thereto a pin 29 which is received in a vertical slot 30 in the arm to prevent turning of the shoe relative to the members 20. A spring 31 is attached to the lever 14 for urging the latter against a stop 32, and, when the lever is against this stop, the shoes 24 overlie and cover the discharge openings 27. If desired the stop 32 may be positioned so that the shoes may move across the discharge openings.

The mode of use of the improved track sander is as follows. When the containers are properly filled with sand and the vehicle is traveling along the trackway, the operator from his station on the platform 7 may grasp the handle 17 and lift the rod 15 to release its engagement with the slot 18. The operating rod 15 may then be moved back and forth to effect oscillation of the feeding and agitating members 20 in the containers. The feeders are moved in one direction against the action of the coiled spring 31, and the latter aids in feeder movement in the opposite direction. As the shoes 24 are moved back and forth over the discharge openings 27, the latter are intermittently uncovered and the sand may flow from the containers through the discharge openings 27 and hose sections 28 onto the tread surfaces of the track rails so that possibility of slippage of the traction wheels is substantially reduced. The oscillatory motion of the feeder members 20 effects agitation of the sand in the containers so that the sand may freely flow through the discharge openings even when the sand is wet or packed. Also, the movement of the shoes back and forth over the discharge openings effectively aids in the feeding of the sand.

As a result of this invention, an improved track sander is provided whereby clogging of the sand, even when wet, in the sand containers is substantially avoided. It will further be evident that by the provision of the oscillatory feeder members and the sliding shoes held in firm frictional contact with the bottom container walls, the sand is effectively fed from the containers onto the treads of the track rails. By the provision of the yielding mounting for the sliding shoes, the latter are at all times closely held in frictional contact with the bottom container walls so that when the shoes cover the container discharge openings, undesired flow of sand from the containers is precluded. Other uses and advantages of the invention will be clearly apparent to those skilled in the art. It will of course be understood that while I have shown two sand boxes and feeders, my invention is not limited to the use of a plurality of such devices, or to any number of them greater than one.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a track sander for wheeled vehicles, the combination comprising a sand container having a bottom discharge opening, and an oscillatory feeder in said container for controlling the flow of sand from said container through said discharge opening, said feeder comprising an oscillatory arm, and a sliding shoe operatively connected to said arm and contacting the bottom

5 container wall, said shoe upon oscillatory motion of said arm moving back and forth over said discharge opening, and yielding means on said arm and acting on said shoe for yieldingly urging said shoe into tight frictional contact with the bottom wall of said container.

2. In a track sander for wheeled vehicles, the combination comprising a sand container having a bottom wall provided with discharge means, 10 a feed control member contacting the bottom container wall for controlling flow of sand from said container through said discharge means, said container and feed control member being mounted for relative movement and effecting opening and closing of said discharge means upon such relative movement, and means for yieldingly maintaining tight frictional contact between said feed control member and the bottom wall of said container including means for causing the exertion by said feed control member of a yielding pressure on said bottom wall.

25 3. In a track sander for wheeled vehicles, the combination comprising a sand container having a bottom wall provided with a discharge opening, and feed control means in said container for controlling the flow of sand from said container through said discharge opening, said container and said feed control means being mounted for relative movement in opposite directions and effecting opening and closing of said discharge 30 opening upon such relative movement, and said feed control means comprising a support, a shoe slidably contacting the bottom container wall for controlling said discharge opening, and yielding means on said support for yieldingly urging said shoe into tight frictional contact with the bottom wall of said container.

4. In a track sander for wheeled vehicles, the combination comprising a sand container having a bottom wall provided with a discharge opening, 40 and feed control means in said container for controlling the flow of sand from said container through said discharge opening, said container and said feed control means being mounted for relative oscillatory movement and effecting opening and closing of said discharge opening upon such relative movement, and said feed control means comprising a support, a shoe operatively connected to said support and slidably contacting the bottom container wall for controlling said discharge opening, and yielding means for yieldingly maintaining tight frictional contact between said shoe and the bottom wall of said container including means for causing the exertion by said shoe of a yielding pressure on said bottom wall.

5. In a track sander for wheeled vehicles, the combination comprising a sand container having a curved bottom wall perforated by a discharge 60 opening, and an oscillatory feeder in said container for controlling the flow of sand from said container through said discharge opening, said feeder comprising an oscillatory arm, a sliding shoe operatively connected to said arm and having a curved shoe portion contacting the curved bottom container wall, said shoe upon oscillatory motion of said arm moving back and forth over said discharge opening, and yielding means on said arm and acting on said shoe for yieldingly urging said shoe into tight frictional contact with the curved bottom wall of said container.

6. In a track sander for wheeled vehicles, the combination comprising a sand container member having a bottom wall provided with discharge 75 means, a feed control member contacting

the bottom wall of said container member for controlling flow of sand through said discharge means, said container member and said feed control member being mounted for relative movement and effecting opening and closing of said discharge means upon such relative movement, and means for yieldingly maintaining tight fric-

tional contact between said feed control member and the bottom wall of said container member including means for yieldingly urging one of said members towards the other in a direction normal to the bottom wall.

LEON E. SIMMONS.
